UNITED STATES PATENT OFFICE.

HENRY FARKOUE, OF BROOKLYN, NEW YORK.

PORTABLE RADIOANTENNA.

Application filed November 24, 1925. Serial No. 71,079.

This invention relates generally to antennas for radio receiving sets, and more particularly of the type known as loop antennas.

5 An object of the invention relates to the provision of a novel form of loop antenna of simple construction and occupying a minimum space, and which may be readily folded into compact form when not in use.

10 For further comprehension of the invention, and of the objects and advantages thereof, reference will be had to the following description and accompanying drawing, and to the appended claims in which the various 15 novel features of the invention are more particularly set forth.

Fig. 1 of the drawings is a general perspective view showing my improved loop antenna as it may be worn upon the person 20 of the user of a portable radio set.

Fig. 2 is an enlarged detail face view of the antenna.

Fig. 3 is an edge view thereof.

Fig. 4 is a perspective view of my loop 25 antenna in a rolled up condition as when not in use.

Fig. 5 is an enlarged fragmentary sectional view taken on the line 5—5 of Figure 3.

In constructing this antenna I make use 30 of a highly flexible insulated wire 10, preferably ten strand silk covered 38 gauge wire. This wire is stitched in as indicated at 11 on a piece of rubberized cloth 12 of rectangular form. I have found that eighty feet of 35 this wire arranged in seventeen turns is satisfactory. The turns of the wire are spaced a slight distance apart, while a comparatively large vacant space is left in the centre. The coil or loop is then covered on 40 both sides with sheets 13 of rubberized cloth which are stitched to one another along the edges together with a binding tape 14. The ends of the wires of the coil are indicated by 15 and 16 and emerge from one side of 45 the device.

The device is provided with a hook 17

fastened on one side whereby suspension is possible to other suitable means, such as an eye in the belt shown in Figure 1, or may be hung over the shoulder or suspended or placed anywhere upon the person of the user. As constructed the natural wave length of the loop is 150 meters, but when used in conjunction with a radio set having variable condensers for tuning the device 50 will respond to and tune to wave lengths of from 200 to 600 meters.

The loop can be folded into a small roll which can easily be placed in a coat pocket, and therefore is serviceable and advantageous for use in hiking or walking trips.

While I have illustrated and described my invention with some degree of particularity, I realize that in practice various alterations therein may be made. I therefore reserve the right and privilege of changing the form of the details of construction or otherwise altering the arrangement of the co-related parts without departing from the spirit and scope of the appended claims.

Having thus described my invention what I claim as new, and desire to protect by Letters Patent of the United States is as follows:

1. In a loop antenna of the class described, having a sheet with wiring stitched thereon; the combination of a sheet placed on one side of said sheet with wiring, another sheet placed on the other side of said sheet with wiring, binding tape placed along the edges of said sheet, and stitching securing said sheets together.

2. In a loop antenna of the class described, having certain turns of wire, the combination of a sheet, stitching, securing said sheet to said turns of wire, a sheet on each side of said sheet with attached wiring, a binding strip along the edges of said sheets, and stitching securing said sheets together.

In testimony whereof I have affixed my signature.

HENRY FARKOUE.
